UNITED STATES PATENT OFFICE

93,961

DESIGN FOR A SHOE

Bertha Arkin, New York, N. Y., assignor to Bancroft Walker Co., Waltham, Mass., a corporation of Massachusetts

Application October 20, 1934, Serial No. 53,705

Term of patent 3½ years

To all whom it may concern:

Be it known that I, BERTHA ARKIN, a citizen of the United States, residing at New York, in the county of New York, and State of New York, have invented a new, original, and ornamental Design for a Shoe, of which the following is a specification, reference being had to the accompanying drawing, forming a part thereof, in which

Fig. 1 is a view in side elevation of a shoe showing my new design, the outline being conventional and shown in dotted lines; and

Fig. 2 is a plan view of the shoe.

I claim:

The ornamental design for a shoe substantially as shown and described.

In testimony whereof, I have affixed my signature hereto.

BERTHA ARKIN.
